Primary Examiner — Catherine Tuttle(74) *Attorney, Agent, or Firm* — Kramer Levin Naftalis & Frankel LLP(57) **CLAIM**

The ornamental design for the sprayer device, as shown and described.

DESCRIPTION

FIG. 1 is a top view showing our new design for a sprayer device;

FIG. 2 is a rear view thereof;

FIG. 3 is a right side view thereof;

FIG. 4 is a front view thereof;

FIG. 5 is a left side view thereof;

FIG. 6 is a bottom plan view thereof; and

FIG. 7 is a perspective view thereof.

FIG. 8 is a top view showing a second embodiment of our new design for a sprayer device;

FIG. 9 is a rear view thereof;

FIG. 10 is a right side view thereof;

FIG. 11 is a front view thereof;

FIG. 12 is a left side view thereof;

FIG. 13 is a bottom plan view thereof; and

FIG. 14 is a perspective view thereof.

FIG. 15 is a top view showing a third embodiment of our new design for a sprayer device;

FIG. 16 is a rear view thereof;

FIG. 17 is a right side view thereof;

FIG. 18 is a front view thereof;

FIG. 19 is a left side view thereof;

FIG. 20 is a bottom plan view thereof; and,

FIG. 21 is a perspective view thereof.

The appearance within the inner circular region of FIGS. 6, 13 and 20 forms no part of the claimed design.
